(57) **CLAIM**

The ornamental design for a wire testing device as shown and described.

DESCRIPTION

FIG. 1 is a front, top, right side isometric perspective view of a first embodiment of a wire testing device in accordance with my design.

FIG. 2 is a rear, bottom, left side isometric perspective view of wire testing device as shown in FIG. 1.

FIG. 3 is a front elevation view of wire testing device as shown in FIG. 1.

FIG. 4 is a rear elevation view of wire testing device as shown in FIG. 1.

FIG. 5 is a right side elevation view of wire testing device as shown in FIG. 1.

FIG. 6 is a left side elevation view of wire testing device as shown in FIG. 1.

FIG. 7 is a top plan view of wire testing device as shown in FIG. 1.

FIG. 8 is a bottom plan view wire testing device as show in FIG. 1; and,

FIG. 9 is a front, top, right side isometric perspective view of wire testing device in an alternative position.

The broken lines illustrate positions of the wire testing device which form no part of claimed design.
